UNITED STATES PATENT OFFICE.

GEORGE A. HOWE, OF PITTSBURGH, PENNSYLVANIA.

APPARATUS FOR CASTING METALS.

1,058,059.

Specification of Letters Patent.

Patented Apr. 8, 1913.

Application filed March 3, 1911. Serial No. 612,019.

To all whom it may concern:

Be it known that I, GEORGE A. HOWE, a citizen of the United States of America, residing at Pittsburgh, in the county of 5 Allegheny and State of Pennsylvania, have invented certain new and useful Improvements in Apparatus for Casting Metals, of which the following is a specification, reference being had therein to the accompanying 10 drawing.

This invention relates to apparatus for casting inlays, bridges, crowns, plates and other structures used in dentistry, and the invention has for its primary object to 15 provide an apparatus for economically and expeditiously drawing metal into every nook, corner and cranny of a matrix or an investment, thereby obtaining most perfect reproductions, without the ordinary and well 20 known conditions endangering the result.

A further object of the invention is to utilize an air compressor or pump for producing a vacuum in an investment holder or a supply of air in a blowpipe, or both as 25 occasion may demand.

The invention in its broadest aspect aims to facilitate the dental practice of producing cast structures of metal, it being a well known fact that difficulty is experienced in 30 properly fusing metal, in maintaining the metal at a proper temperature that it will readily flow by gravity into a matrix or investment, and in obtaining a result that is satisfactory in all instances.

35 I am aware that numerous devices have been devised for creating a blast or vacuum beneath a matrix or an investment for drawing the molten metal into the cavity of the matrix or investment, but such devices have 40 been spasmodic and sudden in their operation to the detriment of a perfect reproduction. For instance, as the operation is invisible, it is impossible to determine whether the molten metal has entered every nook and 45 corner of the matrix, consequently a large percentage of castings are imperfect and useless on account of the sudden blast or vacuum not being of sufficient endurance to completely draw the metal into the cavity.

50 In devising my method of casting, I utilize a continuous vacuum producing apparatus that insures a continuous suction at the bottom of the matrix or investment when the latter is brought into communication 55 with the apparatus, and consequently the molten metal is drawn into every nook and

corner of the matrix or investment cavity. A perfect reproduction is thus made that conforms in every detail to the contour of the cavity in which it is molded.

60 The apparatus will be hereinafter specifically described and then particularly claimed, and reference will now be had to the drawings, wherein there is illustrated a preferred embodiment of the invention, 65 but it is to be understood that the structural elements thereof are susceptible to such changes as fall within the scope of the appended claims.

In the drawings:—Figure 1 is a plan of 70 the apparatus, Fig. 2 is a side elevation of the same, Fig. 3 is a vertical sectional view of the investment holder, Fig. 4 is a longitudinal sectional view of the air compressor, Fig. 5 is a vertical cross sectional view of 75 the same, and Figs. 6 and 7 are detail sectional views of the two-way valve forming part of the apparatus.

75 The reference numeral 1 denotes an electrically operated lathe or other source of power adapted to impart a rotary movement to a tapering spindle 2 and detachably mounted upon said spindle and adapted to rotate therewith is a circular head 3 having a tapering socket 4 to receive the spindle 80 2. The head 3 is inclosed by a sectional metallic casing, comprising a cylindrical shell 5 and end plates 6 and 7 suitably connected to said shell, the end plate 6 having an opening for the hub 8 of the head 3. The metallic casing is arranged eccentrically relatively to the head 3, thereby providing a crescent-shaped compressing chamber 9, the air within said chamber being compressed 85 through the medium of a plurality of spring 90 pressed slides or valves 10 that are normally retained in engagement with the inner walls of the shell 5 by springs 11. The shell 5 has an air inlet nozzle 12 and an air outlet nozzle 13, and the elements 3 to 13 inclusive 95 constitute an air compressor that serves functionally two purposes, namely that of creating a continuous suction or vacuum and that of supplying air to a blowpipe or for other purposes.

100 The air inlet nozzle 12 is connected by a flexible conduit or tube 14 to the nipple 15 of a two-way valve, said valve comprising a sectional pedestal 16 having the sections thereof connected by screws 17 or other fastening means. The confronting faces of the valve sections are provided with vertical 105 110

grooves 18 constituting a bore for a tubular valve stem 19 frictionally held between said sections. The upper end of the valve stem has a suitable knob or handle 20 and intermediate the tubular valve stem there is a partition 21. The walls of the valve stem above the partition are provided with oppositely disposed openings 22 and the wall beneath said partition with a single opening 23. The lower end of the valve stem is open and is adapted to receive air admitted to the base of the valve through notches 24 provided therefor in the lower edge of the pedestal. The section of the pedestal opposite the nipple 15 is provided with a nipple 25 and communication between the nipples 15 and 25 is established by the openings 22, while communication between the base of the pedestal and the nipple 15 is established through the medium of the opening 23 and the open end of the valve stem 19.

The nipple 25 is connected by a flexible conduit or tube 26 to a nipple 27, carried by the outer end of a pipe 28 located in the base 29 of an investment or matrix holder. The inner end of the pipe 28 is connected by an elbow 30 to the reduced end 31 of a stand pipe 32 mounted in the base 29. The upper end of the stand pipe 32 has a circular head 33 provided with a seat 34 and a concavity 35, said concavity being in communication with the flexible conduit or tube 26. Detachably mounted upon the seat 34 of the head 33 is a tapering holder 36 adapted to contain a matrix or investment 37 which is made of the ordinary and well known porous composition, the matrix or investment containing a cavity 38 which has been previously formed by a disappearing mold.

The nozzle 13 is connected to a regulator or valve 39 of a conventional form, and this regulator is connected by a flexible conduit or tube 40 to a conventional form of blowpipe 41 receiving a supply of gas through a flexible conduit or hose 42.

Operation: When the tubular valve stem 19 is raised and communication established between the atmosphere and the nipple 15 by the opening 23, air can be readily drawn into the air compressor and supplied to the blowpipe 41 when the compressor is placed in operation. It is therefore obvious that air can be supplied to the blowpipe, whereby it can be used for various purposes other than with the investment holder. When it is desired to make a casting, the metal is placed upon the top of the investment or matrix and subjected to the flame of the blowpipe which melts the same, and it is in this connection that a continuous supply of air to the blowpipe will permit of the blowpipe properly melting the metal. When that point has been reached that the metal is in a molten condition, the operator immediately pushes or hammers down the tubular valve stem 19

of the two-way valve, thereby shutting off the supply of atmosphere through the lower end of the tubular valve stem 19 and placing the air compressor in communication with the head 33 and the investment holder 36. The air compressor then receives its supply of air through the porous matrix or investment and the suction created by the air compressor draws the molten metal into every part of the cavity 38, causing the metal to remain in engagement with the walls of the cavity until cool. This is due to the fact that the air compressor maintains a continuous vacuum until the tubular valve stem 19 is again raised. The electric lathe can be operated at any desired speed, consequently the exact amount of air supplied to the blowpipe 41 or the intensity of the continuous vacuum in the head 33 can be regulated. The supply of gas to the blowpipe 41 can be regulated in the ordinary manner, while the regulation of the air may be by the valve 39 and the size of the openings 22 and 23.

From the foregoing it will be observed that after placing the electric lathe in operation, the first step is the placing of the metal upon the matrix or investment, then subjecting the metal to the flame of the blowpipe until it has been brought to the proper stage of fluidity, and then drawing the molten metal into the cavity of the matrix or investment by constant and steady vacuum that causes every nook and corner of the cavity to be filled, whereby the casting will conform in all respects to the contour of the original mold.

What is claimed is:

1. In apparatus of the character described, an investment holder, a blow-pipe, and means intermediate said parts and connected thereto for supplying air under pressure to the blow-pipe, said means receiving its air supply through the investment holder or independently thereof at will. 105

2. In apparatus of the character described, an investment holder, a blow-pipe, and means intermediate said parts and connected thereto for supplying air under pressure to the blowpipe, said means receiving its air supply from the investment holder or independently thereof at will, and manually-operated means located within the connections for controlling the source of air supply. 115

3. In apparatus of the character described, an investment holder, a blow-pipe, a device for supplying air under pressure to said blow-pipe, and connections between said device and the investment holder, said connections including an element adapted to control communication between the parts so connected and an independent source of air supply, said element being shiftable to supply the device through the investment or from said independent source at will. 120

4. In apparatus of the character described, 130

an investment holder, a blow-pipe, a device for supplying air under pressure to said blow-pipe, and connections between said device and the investment holder, said connections including an element adapted to control communication between the parts so connected and an independent source of air supply, said element being shiftable to supply the device through the investment or from 5 said independent source at will, said device

being positioned to provide a suction operation on the investment when the latter is placed in communication therewith through the element.

In testimony whereof I affix my signature 15 in the presence of two witnesses.

GEORGE A. HOWE.
